(57) **CLAIM**

The ornamental design for a charging connector cap for an automobile, as shown and described.

DESCRIPTION

FIG. 1 is a perspective view of a charging connector cap for an automobile showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines illustrate portions of the charging connector cap for an automobile and form no part of the claimed design. The dash-dotted lines denote the boundary of the claim and form no part of the claimed design.
